US00D528540S

(12) **United States Design Patent** (10) Patent No.: **US D528,540 S**
Sugihara et al. (45) Date of Patent: **** Sep. 19, 2006**

(54) **COMPUTER SERVER**

(75) Inventors: **Yuichi Sugihara**, Tokyo (JP);
Kenichiro Matsushita, Tokyo (JP)

(73) Assignee: **NEC Corporation**, Tokyo (JP)

(**) Term: **14 Years**

(21) Appl. No.: **29/234,173**

(22) Filed: **Jul. 13, 2005**

(30) **Foreign Application Priority Data**

Jan. 14, 2005 (JP) 2005-000738

(51) **LOC (8) Cl.** **14-02**

(52) **U.S. Cl.** **D14/301**

(58) **Field of Classification Search** D14/349-356,
D14/300, 301, 308; D13/162, 184, 199; 312/223.1-223.2;
